UNITED STATES PATENT OFFICE.

CHARLES H. HAESELER, OF PHILADELPHIA, PENNSYLVANIA.

PERCUSSIVE TOOL.

1,053,383.

Specification of Letters Patent. Patented Feb. 18, 1913.

Application filed March 4, 1911. Serial No. 612,136.

To all whom it may concern:

Be it known that I, CHARLES H. HAESELER, a citizen of the United States of America, and a resident of Philadelphia, county of 5 Philadelphia, and State of Pennsylvania, have invented certain new and useful Improvements in Power-Operated Percussive Tools, of which the following is a specification, reference being had to the accompanying drawings, forming a part thereof.

My invention relates to power operated percussive tools such as rock drills, mining machines, power hammers, pile drivers, and the like, the operation of which is effected 10 by elastic motive fluid under pressure alternately admitted into a working cylinder upon opposite sides of a reciprocating piston freely mounted therein. In a co-pending application, Serial Number 578,149, filed 15 August 20th, 1910, I have disclosed a novel means for cushioning the working piston upon the return stroke, together with means for augmenting the force of the blow imparted upon the forward or working stroke, 20 such means not only tending to increase the speed of movement of the piston but to decrease the amount of motive fluid consumed; and my present invention relates to a specific construction of mechanism adapted to 25 effect this result.

In order that my invention may be thoroughly understood I will now proceed to describe an embodiment thereof, having reference to the accompanying drawings illustrating the same, and will then point out 30 the novel features in claims.

In the drawings: Figure 1 is a view in central longitudinal section of a power rock drill constructed in accordance with my invention. Figs. 2 and 3 are respectively views in side and end elevation of a nut employed as a part of the rotating mechanism thereof.

The rock drill illustrated comprises in 45 general, a main working cylinder 5, a reciprocating piston 6 therein, a distributing valve 7 for admitting and exhausting motive fluid to and from the cylinder below and above the piston, and rotating mechanism by which step by step movements of 50 rotation are imparted to the piston.

The valve 7 is of the piston type and is operated by fluid pressure in one direction or the other, at about the time the piston 55 reaches the end of its stroke in either direction.

The rotating mechanism comprises a rifle bar 8 secured against relative longitudinal movement in the upper head 9 of the drill, ratchet and pawl mechanism 10, by which movements of rotation of the said rifle bar are permitted in one direction but prevented in the other, and a nut 11 secured in the upper end of the piston 6 and fitted to the said rifle bar.

The piston 6 has a cylindrical cavity 12 therein which receives the forward end of the rifle bar 8, and the said forward end of the rifle bar has affixed thereto or formed as a part thereof, a small piston 13, which is fitted to the said cylindrical cavity 12 as will readily be seen by reference to the drawing. If the piston 13 be made removable from the rifle bar, the nut 11 may be made in one part, and such a construction is shown in the co-pending application above referred to, but where the piston is made as a part of the rifle bar it is convenient to make the nut 11 in two parts as is shown in Figs. 2 and 3 of the drawings 50 wherein to facilitate the assembling and disassembly of the parts. When fitted into place the nut 11 is reinforced by the walls of the piston and the fact that it is made in two halves is thus immaterial in the 55 normal operation of the tool.

In the normal operation of the tool, motive fluid, such as air or steam under pressure, is first admitted behind the main piston to move the same forward, the working 90 space in the main cylinder in front of the main piston being at such a time opened to exhaust, then as the piston reaches the end of its forward stroke, motive fluid is admitted in front of the piston to drive the 95 same backward, the previously employed motive fluid at the back of the piston being then permitted to pass to the exhaust. In the forward movement of the piston the ratchet and pawl mechanism 10 permits the 100 rifle bar 8 to rotate, the same being given a movement of rotation throughout a portion of a revolution by means of the coaction of the inclined grooves therein with the complementary projections in the nut 11, while 105 upon the rearward or return movement of the piston 6 the ratchet and pawl mechanism holds the rifle bar stationary and a partial movement of rotation is imparted by the rifle bar to the piston.

Near its forward end the main piston 6 is provided with a circumferential annular

groove or recess 14, the rear end of which is in open communication through a cross passage 15 with the interior of the cylindrical cavity 12. This recess is arranged to come into register with a cross passage 16 arranged in communication with the main forward admission passage 17, whereby as the main piston reaches the end of its forward stroke motive fluid under pressure will be admitted from the said admission passage 17 to the interior of the cylindrical cavity. Then as the main piston commences its rearward movement the piston will move out of registry with the said cross passage 16 and during the entire remainder of the rearward movement of the piston the interior cavity 12 of the piston 6 will be entirely closed. The motive fluid thus admitted to fill the cavity 12 when the piston is in its forward position will be entrapped during the rearward movement thereof, whereby this motive fluid will be gradually compressed during substantially the entire rearward movement of the piston and will act as an efficient cushioning means to prevent the piston from striking the upper head 9. It will, of course, be understood that the effective working area of the fluid on the front end of the main piston is considerably greater than the area of the cavity, so that there will be plenty of power to move the piston backward while at the same time compressing the entrapped motive fluid in the cavity 12; and in addition it will be appreciated that in operation there is a considerable rebound to the main piston following the impact of the drill upon the rock, the momentum acquired in such rebound acting to augment the action of the motive fluid in effecting the return movement of the piston. When the piston has reached the limit of its rearward movement and motive fluid is admitted above it *i. e.* to the rear thereof to again effect a forward movement of the same, motive fluid at such time being exhausted from in front of the piston, such forward movement of the piston will be augmented and accelerated by the energy contained in the fluid compressed as it is to a high degree in the cavity 12. As the piston 6 moves forward and the motive fluid contained therein expands it will be noted that theoretically such expansion will be only to the point of pressure at which the motive fluid is employed. Actually in practice there will be a slight loss due to leakage and it is only this loss which has to be resupplied each time the piston 6 reaches the forward extremity of its stroke. For this reason the duration of time within which the groove 14 and the cross passage 16 are in registry, may be very short; moreover the cross passages 16 and 15 may be very small 65 in cross-sectional area.

As the degree of compression of the motive fluid within the cavity 12 is very great, I have provided the piston 6 with an intermediate packing ring 18 in addition to the forward and rearward packing rings 19 ordinarily employed, the forward packing ring 19 and the intermediate packing ring 18 serving to prevent the escape of this highly compressed motive fluid between the piston and cylinder walls. 70

What I claim is:

1. In an elastic fluid operated percussive tool the combination with a main cylinder, and a percussion piston freely mounted therein and having a cylindrical cavity projecting inward from the rear end thereof, of a cushioning piston mounted in the cylindrical cavity, and held against longitudinal movement relative to the cylinder, and means for admitting elastic motive fluid under pressure to the cylinder, said cylinder and piston being provided with ports and passages arranged to come into register to admit the motive fluid to said cylindrical cavity when the piston is near the end of its forward stroke, and to be out of such registry, so that the motive fluid so admitted will be entrapped in such cavity, in positions of said piston other than near such end of its stroke. 80

2. In an elastic fluid operated percussive tool the combination with a main cylinder and a percussion piston freely mounted therein and having a cylindrical cavity projecting inward from one end thereof, of a cushioning piston mounted in the cylindrical cavity, and held against longitudinal movement relative to the cylinder, and means for admitting elastic motive fluid under pressure to the front end of said cylinder, said percussion piston and cylinder having complementary passages for connecting said cylindrical cavity with the forward end of the cylinder, arranged to come into register as said percussion piston nears the end of its forward stroke, and to pass out of registry as said piston commences its return stroke, so that the motive fluid in said cylindrical cavity will be entrapped therein, and further compressed during substantially the entire return movement of the percussion piston. 100

3. In an elastic fluid operated percussive tool the combination with a main cylinder, and a percussion piston freely mounted therein and having a cylindrical cavity projecting inward from one end thereof, of a cushioning piston mounted in the cylindrical cavity, and held against longitudinal movement relative to the cylinder, and means for admitting elastic motive fluid under pressure to the front end of said cylinder, said percussion piston having an annular circumferential groove therein and a passage connecting said groove with said cylinder. 120

drical cavity, and said cylinder having a motive fluid admission passage, arranged to come into register with said groove as the piston nears the end of its forward stroke, whereby said motive fluid will be entrapped in said cavity and compressed therein during the return movement of said piston.

4. In a rock drill the combination with a main cylinder, and a percussion piston freely mounted therein and having a cylindrical cavity projecting inward from the rear end thereof, of a bar carried by the rear head of the main cylinder and projecting forwardly into said cylindrical cavity, a piston carried by the forward end of said bar and fitted to said cylindrical cavity, and means for admitting elastic motive fluid under pressure to the cylinder, said percussion piston and cylinder having complementary passages for connecting said cylindrical cavity with the forward end of the cylinder, arranged to come into register as said percussion piston nears the end of its forward stroke, and to pass out of registry as said piston commences its return stroke, so that the motive fluid in said cylindrical cavity will be entrapped therein, and fur-

ther compressed during substantially the entire return movement of the percussion piston. 30

5. In a rock drill the combination with a main cylinder, and a percussion piston freely mounted therein and having a cylindrical cavity projecting inward from the rear end thereof, of a bar carried by the rear head of the main cylinder and projecting forwardly into said cylindrical cavity, a piston carried by the forward end of said bar and fitted to said cylindrical cavity, and means for admitting elastic motive fluid under pressure to the front end of said cylinder, said percussion piston having an annular circumferential groove therein and a passage connecting said groove with said cylindrical cavity, and said cylinder having a motive fluid admission passage, arranged to come into register with said groove as the piston nears the end of its forward stroke, whereby said motive fluid will be entrapped in said cavity and compressed therein during the return movement of said piston. 35 40 45 50 55
